UNITED STATES PATENT OFFICE.

ROBERT H. JEFFREY, OF COLUMBUS, OHIO, ASSIGNOR TO THE JEFFREY MANUFACTURING COMPANY, OF COLUMBUS, OHIO, A CORPORATION OF OHIO.

MINING-MACHINE.

1,354,831.

Specification of Letters Patent.

Patented Oct. 5, 1920.

Application filed May 1, 1914, Serial No. 835,757.

Renewed December 28, 1918. Serial No. 268,702.

To all whom it may concern:

Be it known that I, ROBERT H. JEFFREY, citizen of the United States, residing at Columbus, in the county of Franklin and 5 State of Ohio, have invented certain new and useful Improvements in Mining-Machines, of which the following is a specification, reference being had therein to the accompanying drawing.

10 The invention relates more especially to mining machines of either the side cutting type or the vertical cutting type, or both; the invention providing means for cutting a series of horizontal thin or narrow kerfs 15 at distances apart suitable for the subsequent breaking down of the coal, and also for blocking off the coal face by an additional series of vertical kerfs to facilitate the breaking down, preserve the coal principally in large blocks and diminish the 20 amount of slack. The vertical kerfs are formed by the same kerf cutters or saws as are the horizontal kerfs, but for the former purpose the saws are adjusted to vertical 25 position. The invention consists in the parts and combinations thereof hereinafter set forth and claimed.

In order to make the invention more clearly understood I have shown in the accompanying drawings means for carrying 30 it into practical effect, without limiting my improvements, in their useful applications, to the particular construction which, for the purpose of explanation, I have delineated, 35 it being understood that the invention may be embodied in other forms of construction. In the said drawings—

Figure 1 is a plan view of a mining machine embodying the invention, the cutters 40 being shown in full lines as adjusted for horizontal kerf-cutting, and in dotted lines as adjusted for vertical kerf-cutting.

Fig. 2 is a side elevation of the same.

Fig. 3 is a cross section of a part of the 45 machine on line III—III of Fig. 2.

Fig. 4 is a similar view on line IV—IV of Fig. 2.

Fig. 5 is a longitudinal vertical sectional view of the rear portion of the machine on 50 line 5—5 of Fig. 1.

Fig. 6 is a side elevation of a portion of the rear end of the machine.

Referring to the drawings, 1 indicates the bed frame, formed with or bolted to which 55 are upwardly extending posts or brackets

2 having bearings 3. In these bearings are mounted trunnion sleeves 4, which extend beyond the inner faces of the bearings, and on the inner ends of the said sleeves are mounted movable bearings 5. 6. Cast with 60 these bearings are the arms 7 of a yoke or frame 8 having a longitudinal bearing 9, which may be adjusted to a horizontal position or to positions, in the longitudinal vertical plane of the machine, more or less inclined from the horizontal. In this adjustment the sleeves 4 may remain fixed in the bearings 3 or may turn with the bearings 5. 6. The adjustment is effected by a hand wheel 10 at the outer end of the machine 70 fixed on a short shaft 69, the latter being mounted in a bracket bearing 70, fixed on the bed frame. On the shaft 69 is a fixed spur gear 71 which meshes with a spur gear 72 fixed on a shaft 11. This shaft carries 75 and rotates a worm 12 beneath the bearing 6. Fixed on this bearing is a segment 13 of a worm wheel which is engaged and operated by the worm to raise or lower the yoke 8 about the trunnion bearings at 4, 4. 80

14 is a sleeve fitted by bushings 73 to turn within the bearing 9 and having attached to its inner end a yoke 15. 16 is a gear wheel fixed on the sleeve 14, and engaged by a pinion 17 on an adjusting shaft 18. The 85 latter is mounted in a bracket bearing 19 attached to the bearing 9, and has fixed on it an adjusting hand wheel 20. By turning the latter the yoke 15 may be rotated 90° or more to shift the cutters or saws 21 from 90 horizontal to vertical positions, or to any desired angle, as may be required. The said saws are arranged in a series or in multiple and are clamped by spacing sleeves 22, washers 23 and nuts 24 on a shaft 25. Two of 95 said sleeves 22 act as journals, for the rotation of the shaft 25, within bearings 26 attached to the yoke 15. 26 is a latch engageable with the teeth of the gear 16 for holding the yoke and the saws against accidental movement. 100

The rotation of the cutters is effected by the following means, arranged to be operative in any position which the cutters may be caused to assume: 27 is a motor of suitable character mounted on the outer end of the bed frame 1, and having a driving pinion 28 fixed on the inner end of its shaft 29, which latter extends longitudinally of the machine. 30 is a gear wheel fixed on the 110

outer end of a short shaft 31, and meshing with the pinion 28. The shaft 31 is mounted to rotate in a bearing 32, carried by a bracket 33 bolted to the bed frame, and has fixed on its inner end a bevel pinion 34. The latter meshes with a bevel pinion 35 fixed on a transverse shaft 36 mounted to rotate in the sleeves 4, concentric with the axis of the yoke 8. 37 is a bevel pinion 10 fixed on the shaft 36 and meshing with a bevel pinion 38, the latter being fixed on the outer end of a longitudinal shaft 39 which is mounted by bushings 74 to rotate within the sleeve 14, extending through the 15 latter to near the shaft 25. The inner end of the shaft 39 has attached thereto a bevel pinion 40 which meshes with a bevel pinion 41 fixed on the shiftable cutter shaft 25.

During the entering cut of the machine it 20 is fed toward the coal face, whether the cutters be set horizontal or vertical, and thereafter, if the cutters have been entered while horizontal the machine is thereafter fed along the coal face from right to left 25 to make therein multiple narrow or thin horizontal kerfs. For these purposes the machine is provided with feed devices actuated by the said motor 27, the preferred form of which is as follows:

30 42 is a winding drum mounted near the inner end of the bed frame, on which is attached and wound a draft cable 43. The cable passes downward from the drum and under a guide sheave or pulley 44 mounted 35 in a caster block or frame 45, having a tubular spindle rotatably mounted in the bed frame. The arrangement is such that the cable passes downward through the said spindle and under the pulley. The cable 40 can be taken off in any desired direction within a range of about 180°, either toward the face of the coal when the machine is to be fed inward at the right rib to make the entering cut, or away from the machine 45 along the face of the coal to the left rib when the feed is to be parallel, or substantially so, with the coal face. For any such directions of feed the otherwise free end of the cable is anchored by a jack or in any 50 other known manner. The drum has attached thereto a gear wheel 46 and these parts are mounted on a shaft 47 turning in bearings 48 on the bed frame. 49 is a pinion loosely mounted on the motor shaft 29 (see Fig. 1) 55 and having a clutch member 50 on its inner face. 51 is a spur gear fixed on the outer end of a sleeve 52 which surrounds the shaft 29 loosely and is mounted in the bearing 53 on the bed frame. On the inner end of the 60 sleeve 52 is fixed a spur gear 54. 55 is a short shaft mounted in a bearing 56 on the bed frame. On its outer end is fixed a gear wheel 57 and on its inner is fixed a pinion 58. This pinion meshes with the loose gear 65 51 and the gear 57 meshes with the loose

pinion 49. 59 is a double clutch member 70 slidably keyed on the shaft 29 and engageable at will with either the clutch element 50 or the clutch element 60 on the outer end of the sleeve 52, by means of a shifting hand lever 61 and suitable connections. By the gearing described the gear wheel 54 can be driven at either of two speeds from the motor and shaft 29. Thus, if the clutch member 59 be thrown so as to make the 75 pinion 49 fast on the shaft 29 the latter will turn the shaft 55 through the gear 57, and the gear 54 through the pinion 58, gear 51 and sleeve 52, and at a lower speed. If the clutch be caused to connect the shaft 29 directly with the sleeve 52 the gear 54 will be turned in the same direction as before, but at a higher speed, the pinion 58, gear 57 and pinion 49 turning idly. The gear wheel 80 85 54 drives the gear 46 and the winding drum 42 by a gear 62, shaft 63 within the bed frame and pinion 64 meshing with the gear 46, the shaft 63 being mounted in bearings 65 attached to the bed frame.

When the cutters are adjusted vertical, as 90 shown in dotted lines in the drawings, one purpose of which is to form vertical kerfs to be thereafter cross-cut by horizontal kerfs, or to cross cut horizontal kerfs, so as to block out large pieces of coal, the machine 95 is fed toward the coal face by means of the drum 42, as already described, to enter the cutters into the coal as far as may be desired. Thereafter the drum is not used as a feeding means, but the cutters are 100 moved in vertical arcs, around the trunnion center at 4, 4, by means of the hand wheel 20. This means of feeding, by the hand wheel 20, is available, within its limits of movement, to move the cutting devices relative to the bed frame when they are adjusted and in operation for making horizontal kerfs.

To retard the outer end of the machine as against the pull of the cable 42, and keep 110 it directed at the desired angle to the coal face, an unwinding drum 66 and cable 67 are provided. This drum is or may be attached to the outer right hand corner of the bed frame, and the otherwise free end of the cable 67 is anchored at the right rib. The drum is yieldably held, as the machine is fed by the drum 42, and as the cable 67 unwinds, by an adjustable friction brake band or device 68, so that the outer end of the machine 115 120 is allowed to move to the left only about as fast as do the cutting devices.

What I claim is:

1. In a mining machine, the combination of suitable supporting and driving means, 125 narrow kerf cutters arranged in multiple, and means for adjusting the same to cut into or across the face of the coal in horizontal planes, and in planes at an angle to the horizontal; the said parts being mounted 130

on a frame constructed and arranged to slide and be propelled on the mine floor in any direction, irrespective of a track; and means for propelling said frame toward the 5 coal face, and across the same, substantially as set forth.

2. In a mining machine, the combination of suitable supporting and driving means, a rotatable shaft, a plurality of narrow 10 parallel kerf cutters arranged in series along the said shaft and all rigidly secured thereto in common, whereby all of said cutters are similarly held permanently fixed in common relation to the axis of said shaft 15 and are all similarly bodily adjusted when the shaft is adjusted, means for bodily adjusting said cutter shaft from a vertical line to inclined axial lines to cause the cutters either to form kerfs in horizontal 20 planes across the face of the coal or to form kerfs inclined to the horizontal across said face, means for holding the cutter shaft rigidly in position, and power devices for moving the cutters bodily through the coal 25 while forming kerfs either in horizontal planes or in inclined planes.

3. In a mining machine, the combination of suitable supporting and driving means adapted to be advanced, bodily, longitudinally, narrow parallel kerf cutters arranged in multiple, means for adjusting the cutters either to cut across the face of the coal to form kerfs in horizontal planes or to lie in planes inclined to the horizontal 35 and transverse to the lines of advance of the supporting means to form kerfs inclined to the horizontal, or to vertical positions where they form parallel vertical kerfs, means to hold the cutters in position after 40 adjustment, and means for swinging the cutters vertically around a horizontal transverse axis.

4. In a mining machine, the combination of a suitable support, narrow parallel kerf 45 cutters arranged in multiple, a cutter frame having an element carrying the cutters and rotatable vertically around an axis in a longitudinal vertical plane, and a second element mounted on said support and arranged 50 to vibrate around a transverse horizontal axis, means for adjusting the first said frame element around said longitudinal axis, means for adjusting the second frame element around the transverse axis, power 55 mechanism on the support, power devices mounted on the transverse axis, and cutter driving devices actuated by said power devices and rotating bodily around the last said axis.

5. In a mining machine, the combination of suitable supporting driving means, narrow kerf cutters arranged in multiple, and means for adjusting the same to cut into or across the face of the coal in horizontal planes and in planes at an angle to the horizontal, the said supporting means comprising a vertically swingable frame, and means for giving a feeding motion to the same; substantially as set forth. 65

6. In a mining machine, the combination of a bed frame, and multiple kerf cutters movably mounted thereon and adjustable to different angles relative to the horizontal and relative to the coal face; the said bed frame being constructed and arranged 75 to slide and be propelled on the mine floor irrespective of a track; and means for propelling said frame toward the coal face and across the same, substantially as specified. 80

7. In a mining machine, the combination of a bed frame, multiple kerf cutting saws movably mounted thereon and adjustable together around a longitudinal axis and around a transverse axis to different angles 85 relative to the bed frame and to the coal face, and a cable feed mechanism for moving the bed frame parallel with the planes of the saws; substantially as set forth.

8. In a mining machine, the combination of a bed frame, a cutter frame mounted on the bed frame on a longitudinal axis, multiple parallel kerf cutters mounted on the cutter frame, means for adjusting the cutter frame around its axis to change the 95 angles of the cutters, means for feeding the cutters upward and downward, and means for feeding the bed frame horizontally; substantially as set forth. 90

9. In a mining machine, the combination of a bed frame, a cutter frame mounted on the bed frame on an axis which may be directed toward the coal face, the said cutter frame having a part which is movable relative to the said axis, multiple kerf cutting 100 saws supported on the said movable part of the cutter frame, means for adjusting the cutter frame about its said axis, means for feeding the movable part of the cutter frame relative to its supporting part, and 105 means for feeding the bed frame horizontally; substantially as set forth. 110

In testimony whereof I affix my signature in presence of two witnesses.

ROBERT H. JEFFREY.
